United States Patent Office.

CHARLES C. SAVERY, OF PHILADELPHIA, PENNSYLVANIA.

Letters Patent No. 96,486, dated November 2, 1869.

IMPROVED WATER-COOLER AND REFRIGERATOR.

The Schedule referred to in these Letters Patent and making part of the same.

To all whom it may concern:

Be it known that I, CHARLES C. SAVERY, of Philadelphia, in the county of Philadelphia, and State of Pennsylvania, have invented an Improved Water-Cooler and Refrigerator; and I do hereby declare that the following is a full and exact description thereof, reference being had to the accompanying drawings, making part of this specification—

Figure 1 being a front elevation of the water-cooler and refrigerator, set in brick-work.

Figure 2, a central vertical section of the same, in a plane cutting from front to rear thereof.

Figure 3, a vertical section thereof, in a plane cutting from side to side, at right angles to the former section.

Figure 4, a horizontal section of the same, looking upward.

Like letters designate corresponding parts in all of the figures.

This invention is a combined water-cooler and refrigerator, made of cast-iron, and having the inner surfaces of both the air-chamber A and water-tank B enamelled, as indicated at *i*, and also the outside of the bottom of the water-tank (which is cast or formed separately from the air-chamber) similarly enamelled, the same being partly exposed to moisture in the interior of the air-chamber, so that no part is liable to oxidation.

The invention is designed especially as a cellar-refrigerator, and it is enclosed in suitable brick-work, C, or otherwise set, so as to be stationary, or a fixture of the cellar or room in which it is located; and herein is constituted one feature of improvement.

The brick-work surrounds and protects it from the heat of the surrounding air, and there may be a door, *r*, opening into the brick-work, in addition to the door *s*, of the refrigerator proper.

The most important feature of my invention consists in the inclination of the top *a*, of the air-chamber A, backward from the front opening or door thereof, and the formation of an opening, *c*, in the same, occupying the greater part thereof, and having a curved or semicircular form on the front edge, or such other form as to effect the purpose intended, namely, to conduct the water, which condenses on the under surface of the air-chamber top, backward, so that it will run down the back of the air-chamber, and not drip upon the articles placed in the refrigerator.

The bottom *b*, of the water-tank above, is also in-

clined so as to fit over the opening *c*, and cover the same.

A depression, instead of an opening, in the top of the air-chamber A, with similarly-shaped edges, would effect the same object, but not so conveniently as the construction represented.

The bottom *d*, of the air-chamber, is also slightly inclined from front to back, as represented in fig. 2, for the purpose of conducting the drippings to the back part of the chamber, and of preventing their flowing out at the front opening. The water thus collected may be drained off, through an outlet at the back and bottom of the air-chamber, or it may be wiped up with a sponge or cloth, as occasion requires.

The water-tank being cast separately from the air-chamber, it is secured upon the top of the latter by means of two open or forked lugs, *ff*, projecting from each side of the tank, and staples or ears, *gg*, in corresponding positions, cast upon the sides of the air-chamber, and connecting the said lugs and ears, respectively, by bolts, *hh*, hooking into the ears, and secured in the lugs by screw-threads and nuts. The joints between the two castings are then made airtight by cement.

The water is drawn from the water-tank at the front, through a pipe, *k*, leading from the back thereof, and a spigot, *l*, and there may be another pipe and spigot, *m*, at one side.

The brackets *n*, *n*, which support the grates or shelves in the air-chamber, are made of metal, tinned, and are secured to the sides by bolts *pp*, and nuts.

What I claim as my invention, and desire to secure by Letters Patent, is—

The construction of the stationary combined water-cooler and refrigerator, having the air-chamber A, of iron, enamelled on the interior surface, and its bottom *d* inclined from the door, in its front side, backward, and the water-tank B, of iron, enamelled both on the interior and under surface, and secured upon the top of the air-chamber as herein specified.

Also, in combination with the foregoing, the semi-circular or equivalent opening *c*, in the inclined top *a* of the air-chamber, beneath the bottom of the water-tank, for the purpose set forth.

CHARLES C. SAVERY.
